UNITED STATES PATENT OFFICE.

BAY M. SKEELS, OF BUFFALO, NEW YORK.

DEVICE FOR WRAPPING OR FORMING CIGARETTES.

1,266,725.

Specification of Letters Patent. Patented May 21, 1918.

Application filed June 13, 1914, Serial No. 844,998. Renewed December 1, 1917. Serial No. 204,886.

To all whom it may concern:

Be it known that I, RAY M. SKEELS, a citizen of the United States, and a resident of Buffalo, in the county of Erie and State of New York, have made a new and useful Improvement in Devices for Wrapping or Forming Cigarettes, of which the following is a specification.

This invention relates to a device for 10 wrapping or forming cigarettes and one of the principal objects of the invention contemplates the provision of means for forming a cigarette of loose tobacco and an ordinary cigarette paper with a minimum consumption of time and labor and with a maximum degree of proficiency.

Another object of the invention is to provide a cigarette roller including an inner tube, an outer tube and a forming band or 20 strip adapted to coact in compressing a portion of loose tobacco and rolling a cigarette paper around the tobacco for forming a cigarette.

A further object of the invention is to 25 provide a device of the class described which will be extremely simple, durable, efficient in operation and inexpensive to manufacture.

With these and other objects in view 30 which will become apparent as the description proceeds, the invention resides in the construction, combination and arrangement of parts hereinafter more fully described and claimed, and illustrated in the accompanying drawing, in which like characters of 35 reference indicate like parts throughout the several figures, of which—

Figure 1 represents a perspective view of 40 the device, the forming band being removed.

Fig. 2 represents a central longitudinal 45 sectional view through the same.

Fig. 3 represents a vertical transverse sectional view of the device showing one step 50 in the operation of rolling a cigarette.

Fig. 4 represents a view similar to Fig. 3, showing another step in the operation, and

Fig. 5 represents a view similar to Fig. 3, showing still another step in the operation.

Referring more particularly to the drawing, the invention comprises an inner tube 5 formed of any desirable material, and provided with substantially heavy closed ends 6, said tube and ends being formed if desirable from a single piece of metal, the tube 55 being provided on one side with a longitudinal slot 7 running the entire length of the

tube, said slot terminating at its ends at the end walls of the tube and being bounded at its edges by the parallel rounded edges 8 formed by the slot. 60

An outer tube 9 is provided and surrounds the inner tube, said inner tube being rotatable relatively to the outer tube and the outer tube is provided with a slot or opening 10 corresponding in width and length to the 65 slot in the inner tube and said outer tube at its ends projects slightly beyond the end walls 6 of the inner tube and is housed at each end within an annular groove 11 formed in the inner face of buttons 12, which buttons are secured to the end walls 6 of the inner tube by any suitable means, said means in the present embodiment including studs 13 projecting centrally from the end walls 6 through central openings in the buttons 12, 70 75 said buttons being keyed as at 14 to the studs, whereby, as the buttons are turned the inner tube will be rotated relatively to the outer tube.

A forming band or strip 15 is provided 80 which is of a width equal to the length of the slots in the tubes, and substantially equal in width to the length of the ordinary cigarette paper, said forming band being composed of paper, parchment, silk, rubber, or 85 any other suitable fabric.

The operation of the device may be briefly described as follows:

The device may be held in the center in a horizontal position between the thumb and 90 first two fingers of the left hand and the inner tube turned by means of the right hand end button so as to bring the slots in the inner and outer tube into alinement. When in this position, the forming band is placed 95 in the opening in the position indicated in Fig. 3 so that its short end 19 is disposed toward, and its long end away from, the operator, and tobacco is then poured into the inner tube upon the forming band level with 100 the edges of the inner tube and is packed down with the first two fingers of the right and left hand of the operator, and a cigarette paper indicated at 17 is then placed with one edge touching the forming band 105 adjacent the rear edge of the inner tube, the paper lying substantially flat toward the operator.

The outer tube being then held firmly, the inner tube is turned toward or away from 110 the operator into the position shown in Fig. 4 to leave a slight opening 18 extend-

ing longitudinally of the device through which opening the two ends of the forming band extend and the edge portion of the paper extends, and the tubes in this position are held firmly in one hand while the end of the forming band nearest the operator indicated at 19 is pulled toward the operator, thus compressing the tobacco within the chamber and pulling the paper around the same in the manner indicated in Fig. 5. This operation is continued until about one-fourth of an inch of the edge of the cigarette paper is left exposed, and this exposed edge is then wetted allowing it to adhere to the back portion of the forming band, or that portion away from the operator, and the pulling operation is then continued in the same direction as before until the wet edge of the cigarette paper passes into the chamber and adheres to the paper near the other edge which has passed up in forming the cigarette. This operation having been completed the outer tube is then turned to again bring the slots into alignment and the finished cigarette may be removed from the device.

One of the important advantages of this device is that a piece of tobacco leaf may be used in forming the cigarette, in place of the ordinary paper, so that an all tobacco cigarette may be produced.

Although I have described the preferred embodiment of my invention, I may desire to make such changes in the construction, combination and arrangement of parts thereof, as do not depart from the spirit of the invention and the scope of the appended claims.

I claim:

40 1. A cigarette former comprising an inner tube having end walls and being open from end to end along one side, an outer tube within which the inner tube is rotatably positioned, said outer tube provided on one 45 side with an opening substantially of the same dimensions as the opening of the inner

tube, buttons suitably secured to the end walls of the inner tube, whereby the latter may be rotated relatively to the outer tube, the ends of said outer tube projecting beyond the ends of the inner tube, and being housed in annular channels formed in the inner faces of said buttons, and a forming band composed of suitable material and adapted to co-act with the forming device in compressing a portion of tobacco and rolling a paper around the same within the inner tube, substantially as described. 50 55

2 A device of the class described comprising an inner tube, an outer tube, said inner tube being rotatable relatively to the outer tube, said inner and outer tubes each provided along one side with a longitudinally extending opening, the edges of the openings being rounded, buttons secured to the inner tube at its ends, said buttons at their edges overhanging the outer tube, said outer tube extending at its ends beyond the inner tube, said buttons provided with grooves into which the ends of the outer tube extend, 60 65 and a forming band of a width substantially equal to the length of the openings in the inner and outer tubes, and adapted to co-act with said tubes in forming a cigarette, substantially as described. 70 75

3. The herein described cigarette former comprising an outer tube having a longitudinally extending slot in one side thereof, an inner tube positioned for rotation within the outer tube and provided with a slot 80 adapted to be brought into and moved out of registration with the slot in the outer tube, buttons carried at the ends of the inner tube and providing portions overhanging the ends of the outer tube journaling the latter, and a forming band adapted to co-act with the tubes in forming a cigarette, substantially as described. 85
